APPARATUS FOR BURNING SOLID FUEL

Rutherford H. Hunter, Wooster, Ohio

Application December 28, 1933, Serial No. 704,238

20 Claims. (Cl. 110—32)

This invention relates to improvements in apparatus for burning solid fuel, and while intended for use generally wherever it may be advantageously employed, it is particularly adapted for embodiment in a hot air furnace in which connection it will be illustrated in drawings and hereinafter described:

Objects of the invention which may be considered collectively and independently are:

- To provide a solid fuel burning apparatus of simple, durable construction which will be extremely economical in operation and very efficient in use; to provide a furnace having a chamber adapted to hold a supply of solid fuel; to provide efficient means for progressively feeding the fuel to a retort or combustion chamber; to provide efficient means for cooling said hopper and maintaining the same at a relatively low temperature; to provide highly efficient radiating means for heat generated in said combustion chamber, and to provide a combustion chamber which will effect a maximum consumption of gases generated by combustion and will reduce to a minimum the smoke emitted therefrom.
- Other objects and advantages of the invention will be understood from the following description taken in connection with the accompanying drawings in which there is shown an illustrated embodiment thereof, it being understood that the invention is not confined to the particular adaptation illustrated, and that changes and modifications may be made or resort had to substitutions which come within the scope of the claims hereinto appended.
- In the drawings like characters of reference are employed to designate like elements as the same appear in the several views.

Figure 1 is a front elevational view of a hot air furnace constructed in accordance with this invention;

Figure 2 is a horizontal sectional view taken as indicated by the line 2—2 of Figure 1;

Figure 3 is a vertical sectional view taken as indicated by the line 3—3 of Figure 1;

Figure 4 is a vertical, sectional view taken as indicated by the line 4—4 of Figure 2;

Figure 5 is a horizontal, sectional view taken as indicated by the line 5—5 of Figure 4;

Figure 6 is a fragmentary view showing in vertical section certain portions of the device herein disclosed;

Figure 7 is a fragmentary view taken in horizontal section as indicated by the lines 7—7 of Figure 3;

Figure 8 is a plan view of the feeding cam employed in reducing the invention to practice,

Figure 9 is a bottom view of same,

Figure 10 is a plan view showing part of the operating mechanism employed in carrying out the invention;

Figure 11 is a front, elevational view of the centrifugally operating clutch collar employed in the draft operating mechanism herein described.

In the particular embodiment of the invention shown in the drawings, there is illustrated a base section comprising a bottom plate 10 having parallel upstanding flanges 11 and 12, forming a groove 13 therebetween for receiving the lower edge of the ash pit section 14. The rearwardly presented portion of the ash pit section 14 corresponds in shape to approximately one-half of a hollow frustum of a cone, positioned with its smaller diameter at the upper end thereof.

The walls of the section 14 extend forwardly in the form of a rectangular box-like extension 19 leading to a forward wall 16 which is provided with a door opening 17 whereby access may be had to the ash pit 15. The opening 17 is provided with an ash pit door 18 which in turn is provided with a draft opening and a draft door 20. The upper wall of the box-like extension 19 and the upper edge of the rear half of the section 14 are provided with a groove 22 for receiving the lower portion of the section 25.

The numeral 25 denotes a retort or fire box section in the form of a hollow truncated cone which is positioned on the section 14 with the lower edge portion thereof received in the annular groove 22.

The section 25 is relatively thicker at the upper edge thereof, being provided with an outwardly projecting circumferentially extending flange 26. The section 25 is provided in the upper edge thereof with a concentrically arranged annular groove 27.

Numerical 28 denotes a middle section which is also in the shape of an inverted hollow truncated cone, having its lower edge portion entered in the groove 27 of the section 25. The upper edge portion of the section 28 is provided with an outwardly projecting circumferentially extending flange 29 which is provided in the upper edge thereof with a concentrically arranged groove 30.

The section 28 is provided at the forward side thereof with a box-like extension 31 which leads to the opening 34 in the forward wall 16, thereby providing means whereby access may be had to the combustion chamber 32. A suitable door 55

33 is hinged to the forward walls 16 to close the opening 32.

The numeral 35 denotes a section which forms the top and the inner wall which incloses the annular combustion chamber 32.

The section 35, as shown in the drawings, is cast in one piece and includes the upper wall 35a in the form of a hollow truncated cone. The outer edge of the wall 35a is provided with a circumferentially extending downwardly presented flange 36 which is received in the groove 30 in the upper edge of the section 28. The section 35 also includes an inner wall which follows the contour of an inverted hollow truncated cone 15 which extends downwardly and terminates in an inwardly curved portion 35c which is positioned in a horizontal plane just above the horizontal plane of upper edge of the section 14. The reference character 35d denotes a cylindrical portion which is continued upwardly, which meets the curved portion 35c at a sharp angle and projects upwardly therefrom, thus forming a cylindrical feed cavity 37. The cylindrical portion 35d is offset smaller at the upper end thereof to provide an annular shoulder 38 on the exterior surface thereof, and with a downwardly presented, annular shoulder 39 on the interior surface thereof.

The portion of the section 35d extending above the shoulder 39 is solid and is provided with an axial bore 40 and a plurality of openings 41 which extend vertically therethrough, and are arranged in spaced relation around the bore 40. The openings 41 may be of any suitable cross-sectional shape, and are preferably tapered with the smaller end of the openings presented upwardly.

The central portion of the wall 35b is enlarged to space this portion of the wall outwardly 40 in respect to conical surface of the upper and lower portions thereof, and a slightly smaller hollow truncated cone 45 is positioned within the conical portion 35b to inclose the space 46. The wall 35b is provided along a horizontal plane 45 substantially coincident with the plane of the upper edge of section 25, with the circumferentially extending series of spaced openings 47 forming passages which communicate with the enclosed space 46 and the combustion chamber 32.

50. The enlarged portion of the wall 35b is extended outwardly, then inwardly at a sharp angle to form the substantially annular portion 35e and to provide an enlargement of the space 46 for the purpose to be herein and after described.

55. The numeral 50 denotes a conical hopper, which terminates at the lower end thereof with the hollow cylindrical portion 51 which is fitted over the reduced upper end of the cylindrical portion 35d. The conical portion 50 of the hopper terminates at the upper end thereof in a cylindrical portion 52 in which is fitted a hollow cylinder 53.

60. The cylindrical portion 53 is closed at the upper end thereof with a wall 54 which projects outwardly beyond the outer edge of the cylinder 53 and extends forwardly and terminates in a shelf, which is supported by the forward wall 16.

65. The upper wall 54 is provided with a bore 55 which is positioned to receive a tubular shaft 56, which extends axially through the cylindrical portion 53 of the hopper 50. The shaft 56 which extends through the bore 55 and projects upwardly beyond the top 54 and is provided on the upper end thereof with a wheel 57 which is fixedly secured thereto, a suitable anti-friction bearing

58 being mounted between the lower face of the hub of the wheel 57 and the top 54.

The numeral 60 denotes a disk which is fitted on the shaft 56 and which covers the reduced upper end of the cylindrical portion 35d. The disk 60 is provided with an opening 61 which as shown in the drawings is in the form of a sector adapted when the disk 60 is rotated to successively expose the upper ends of the openings 41.

The numeral 62 denotes a split collar which is frictionally secured to the shaft 56 by means of bolts 63 which are mounted in suitable openings in the radial wings 62a whereby the collar 62 will turn with the shaft 56. The collar 62 is provided on the lower edge thereof with a downwardly projecting lug 64 which is entered in a suitable notch 65 in the plate 60 whereby the plate 60 will turn with the shaft 56.

The shaft 56 is provided with a similar disk 66 which is positioned against the shoulder 39 on the reduced portion 35d to cover the lower ends of the openings 41. The plate 66 is also provided with an opening 67 which may be of any suitable shape and through which fuel will be successively released from the lower ends of the openings 41. The opening 67 in the plate 66 is positioned diametrically opposite the openings 61 in the plate 60.

The shaft 56 is provided at the lower end thereof with a cam feed wheel 70 having a hub 71. The numeral 72 denotes a collar which is similar to the collar 62 and which extends between the plate 66 and the hub 71. The collar 72 is split and is provided with radial flanges 73 for receiving the bolts 74, which are employed to frictionally secure the collar 72 to the hollow shaft 56.

The collar 72 is provided at the upper end thereof with a lug 75, which is received in a notch 68 in the plate 66 to provide a positive driving connection between the plate 66 and the shaft 56. The collar 72 is likewise provided on the lower edge thereof with downwardly projecting lugs, which are received in seats 77 in the hub 71, whereby the cam 70 will turn with the shaft 56. The cam feed wheel 70 is provided with arms which project outwardly from diametrically opposite sides of the hub 71, and are provided with spirally disposed faces adapted to operate as hereinafter set forth. The top walls 70a of said arms are flat, are disposed immediately below the discharge end of the cylindrical cavity 37 and extend beyond the cylindrical plane of said cavity. Each arm on said cam feed wheel 70 is provided on the force exciting side thereof with a downwardly depending flange 70b which extends between the top wall of each arm and the grate to be hereinafter described. The inner end portions of the flanges 70b are disposed in concentric relation to the hub 71 thereby forming an annular cavity 70c.

The numeral 80 denotes a hollow shaft which is rotatably nested in the bore of the shaft 56 and which projects from each end thereof. The shaft 80 is provided on the upwardly projecting end thereof with a wheel 81, a suitable anti-friction bearing 82 being employed between the hub thereof and the wheel 57.

A circular grate 83 is secured to the lower end of the shaft 80. While any suitable circular grate may be employed, in the drawings there is shown a grate 83 having a central portion 84 which is secured to the shaft 80 by means of the pin 85 or other suitable means. The central portion of the grate 83 is preferably solid and

is provided with a downwardly offset marginal portion 86. The numeral 87 denotes the annular outer portion of the grate 83. The annular portion 87 is provided with a downwardly inclined inner marginal edge which is supported on the marginal portion 86 of the portion 83 a layer of fire clay or suitable fire resistant cement 88 being employed to firmly hold the portion 87 on the portion 84. The annular portion 87 is provided with suitable radial slots 89 forming bars therebetween.

The top wall 35a is provided at the rearwardly presented side thereof with an upwardly presented nipple 90 having a bore 91 communicating with the combustion chamber 32. The numeral 92 denotes an elbow which is operatively connected to the upper portion of an outlet box 93. The outlet box is provided at each lateral side thereof with an extension in the form of a rectangular box 94 which conforms to the shape of the casing 95. In the particular adaptation of the invention the casing 95 is of hexagonal shape and the boxes 94 extend forwardly, in parallel relation to the lateral sides thereof, terminating 25 in the closed ends 94a. The numeral 96 denotes a horizontal partition which extends through the outlet box 93 and is continued through the extension boxes 94 to a point adjacent the forward ends thereof thereby forming an upper chamber 97 and a lower chamber 98 which communicate at the forwardly presented ends thereof thereby forming two continuous smoke passages. The outlet box 93 is provided on the rear side thereof with two smoke flues 99 and 100. The flue 99 30 communicates with the upper chamber 97 and is positioned directly opposite the discharge end of the elbow 92. The flue 100 is positioned below the flue 99 and communicates with the lower chamber 98. 35

40 The upper flue 99 is provided with a suitable damper 101 and both of the flues 99 and 100 are operatively connected to a chimney or to a smoke pipe leading thereto.

It will be seen that when the damper 101 is operated to an open position that the smoke and unburned gases generated by combustion will escape directly through the flue 99. When the damper 101 is operated to close the outlet flue 99 the smoke will travel through the chamber 97 to the forwardly presented ends of the boxes 94 and through the chamber 98 through which it will travel and escape through the flue 100.

The tubular shaft 80 is provided at the top thereof with a closure disk 104 having spaced, 55 spring prongs 105 which are entered in the upper end of the bore of said shaft whereby the disk 104 may be operated to entirely close the upper end of said tubular shaft 80 or adjusted to regulate the amount of air admitted thereto. The shaft 80 is open at the lower end thereof thereby providing a trickle draft which may be accurately regulated by manipulating the disk 104.

The wall of the tube 80 is provided with openings 106 through which air will be admitted to 60 the hub cavity 70c of the cam 70.

The wall of the upper portion 53 of the hopper 50 is provided at the forwardly presented side thereof with a box-like extension which leads to the door opening 108 in the wall 16 through which 65 coal or other solid fuel is admitted to the hopper 50. The opening 108 is provided with a suitable door 109 which is hingedly mounted on the wall 16.

One side wall of the extension 107 is provided 70 with a screened opening 110 and a tube 111 is

operatively secured in said opening. The tube 111 leads to the wall of the truncated cone 45 and is operatively secured thereto so as to communicate with the cavity 46. The door 109 is provided with an elongated opening 112 for admitting air to the tube 111 whereby air will be drawn through the openings 47 to assist in the burning of unconsumed gases in the combustion chamber 32. The numeral 113 denotes a damper or valve which is operatively mounted in the tube 10 111 and the numeral 114 denotes a damper shaft which projects through a suitable bore in the forward wall 16 and is provided with a knob 115 which may be operated to regulate the opening 15 in the tube 111.

The numeral 116 denotes a shell which is substantially larger than the cylindrical portion 53 and is secured to the top wall 54 to extend downwardly therefrom in spaced parallel relation to the walls of the portion 53 and in spaced relation to the hopper 50 thus providing a space 117. The top wall 54 is provided with a slot 118 which communicates with the space 117. The lower end of the shell 116 terminates in spaced relation to the rounded portion 35c and forms a space 20 25 119 which communicates with the space 117 thereby forming a continuous passage through which air will be drawn downwardly through the opening 118 to the bottom of the cavity of the section 35 whereupon it will be heated by contact with the wall of the section 35 and will travel upwardly through the space 119. Means is thus provided for maintaining fuel in the hopper 50 at a relatively low temperature and for preventing the overheating of the portions of 30 35 the wall of the section 35 which are subjected to high temperature. The wheel 57 is provided with a suitable clutch band 120 which is held in place thereon by means of the clips 121 or other suitable means. The band 120 is provided on 40 one end thereof with a suitable eye 122 which is secured to one end of a lever 123. The other end of the band 120 is provided with an outwardly projecting arm 124. The arm 124 is provided with an ear 125 which projects over the lever 45 123 and is pivotally secured thereto at a point intermediate the length of the lever 123.

The numeral 126 denotes an electrically operated motor and the numeral 127 a suitable reduction gear unit. The reduction unit 127 is 50 provided with an eccentrically mounted wheel 128 which is driven by the motor 126. The wheel 128 is provided with a collar 129 and the collar 129 is provided with an outwardly projecting pitman 130. The outer end of the pitman 55 130 is pivotally secured to the lever 123 by means of the pin 131 whereby the motor 126, when operated, will cause rocking the lever 123. It will be seen that when the pitman 130 is operated to exert a pulling force on the outer end of the 60 lever 123 that the band 120 will be contracted and that the wheel 57 will be given a short clockwise rotary movement. As the wheel 57 is thus intermittently moved by the operation of the motor 126, the movement is communicated 65 through the shaft 56 to the feed cam 70. The disks 60 and 66 are likewise driven by said shaft through the operation of the motor 126.

The wheel 81 is provided with a similar band 132 which is held in place thereon by the clips 70 133 or other suitable means. The band 132 is provided at one end thereof with an ear 134 to which is pivotally secured a lever 135. The other end 132 of the band is provided with an outwardly projecting ear 136 which is pivotally 75

secured to the lever member 135. The numeral 137 denotes a brake operating rod which when a pull is exerted thereon moves the member 135 to contract the band 132 and move the wheel 81 in a direction opposite the described movement of the wheel 57.

The numeral 138 denotes a bracket which is secured to the top wall and which projects over the rim of the wheel 57. A short lever 139 is 10 fulcrumed to the lower side of the bracket 138 for movement in a horizontal plane. The rod 137 is connected to one end of the lever 139. The other end of the lever 139 projects over the rim of the wheel 57 and is provided with an inclined face which is adapted to be engaged by a pin 140 which is inserted in a suitable bore in the rim of the wheel 57. It will be seen that the wheel 57 when intermittently operated as hereinbefore described will, upon each rotation, 20 bring the pin 140 into contact with the inclined face of the lever 139, and cause a quick movement of said lever on the bracket 138. This movement will operate to contract the brake 132 and move the wheel 81 in a direction opposite the 25 direction of movement of the wheel 57. The wheel 81, being thus moved at each rotation of the wheel 57, causes a similar rotatable movement of the shaft 80 and the grate 83 thus providing means whereby the feed cam 70 and the grate 83 30 will be moved in opposite directions.

The drive shaft 141 of the motor 126 projects from the forward side thereof and is provided with a hub 142 on which is rotatably mounted a collar 143. The collar 143 projects forwardly from the forward face of the hub 142 to expose the inner circumferential edge of the collar 143. Two flat members 144 and 145 which are spaced apart and fulcrumed at opposite ends thereof to the forward face of the hub 142. Each 35 of the members 144 and 145 is provided with a rounded face adapted to fit against the inner circumferential edge of the collar 143. The members 144 and 145 are normally held out of contact with the collar 143 by a spring 146 which is secured to each of said members. A draft operating device 147 is provided with a drive wheel 148 which is operatively connected to the collar 143 by the drive belt 149. It will be seen that the operation of the motor 126 will cause the members 40 144 and 145 to be forced outwardly by centrifugal force into engagement with the collar 143, thus rotating the collar with the hub 142 and operating the draft operating device 147. The draft operating device 147 shown consists of a reel on 45 which is wound a chain 150, which is operatively attached to the draft door 20. When the draft door has been raised to its limit the members 144 and 145 will slip in the collar thereby holding the draft door 20 in an open position as 50 long as the motor 126 is operated. When the motor 126 is not in operation the spring 146 will move the members 144 and 145 toward each other 55 releasing the collar 143 and permitting the draft door 20 to fall to a closed position.

The outer casing or jacket 95 may be of any suitable shape or design and may be formed of any suitable material. In the drawings there is shown a hexagonal jacket 95 consisting of the front wall 16 and five panels 16a of approximately the same size, which are supported at the corners by the posts 153 preferably in the form of angle bars as shown in the drawings. The panels 16a extend upwardly to the horizontal plane of the top wall 54 and are provided at the upper edge thereof with an inwardly projecting flange 154.

The numeral 155 denotes suitable cold air inlet openings which are formed in one or more of the panels 16a of the jacket 95 adjacent the lower edges thereof.

The numeral 156 denotes a manifold in the form of a box having an outer wall 157 supported on the flanges 154; a relatively shorter inner wall 158 supported on the marginal portion of the top wall 54 and an inclined top wall 159. The main portion of the inner wall 158 is of cylindrical contour and is disposed in alignment with the casing 116. Each end of the manifold 156 terminates in an end wall 160 which walls are parallel and are disposed in the extended plane of the side walls of the extension 107. The numeral 15 160a denotes the front wall of the manifold 156 which is positioned in parallel, spaced relation to the plane of the front wall 16.

The outer wall 157 of the manifold 156 is provided with suitable distributing openings to which 20 suitable pipes 161 may be connected to operatively connect the furnace to a heating system. Coal or other solid fuel of suitable fineness is placed in the hopper 50 through the door opening 108. The motor 126 is operatively connected to a source 25 of electrical energy, thus imparting a series of regularly recurring rotary movements to the wheel 57 and causing a like movement of the plate 60. As the opening 61 in the plate 60 passes over each chamber 41 the chamber is filled with 30 fuel. As the opening 67 in the plate 66 is diametrically opposed the opening 61 the contents of each chamber 41 will be discharged when the opening 67 registers therewith.

The fuel falls downwardly and is deposited on 35 the solid central portion 84 of the grate 83. As the cam 70 is fixed to the shaft 56, it is likewise rotated thus forcing the fuel outwardly on to the grate 83. When a sufficient quantity of fuel has been thus fed to the combustion chamber 32, 40 access is had thereto through the door 33 and the fuel is ignited. As the central portion of the grate is solid the area of combustion will be substantially confined to the vicinity of the annular portion of the grate containing the radial slots 45 89. With each rotation of the shaft 56 the pin 140 engages the lever 139 and contracts the 50 brake band 132 thus imparting a sudden opposite rotary movement to the shaft 80 and to the grate 83 whereby ashes will be sifted through the slots 55 89 and will fall to the ash pit 15.

It will be seen that while the motor 126 is operating that the draft door 20 is held in an open position as hereinbefore described. Obviously, the motor 126 may be controlled by a thermostatic apparatus positioned in the area to be heated and operatively connected in an electric circuit with the motor 126.

During the operation of the apparatus herein described, air will pass downwardly through the opening 118 to the space 117 and will pass around the lower edge of the casing 116 to the space 119 where it will be heated and will flow upwardly to the manifold 156.

The passage of cold air through the spaces 117 65 and 119 will maintain the hopper 50 at a relatively low temperature which will prevent coking or overheating of the coal or other fuel in said hopper and permit free passage of the fuel to and from the chambers 41. Air will pass 70 through the openings 112 to the opening 110 where it will be drawn downwardly through the pipe 111 by the draft of the furnace to the annular space 46 from which it will be drawn through the openings 47 into the combustion 75

chamber 32. The air thus drawn into the combustion chamber is preheated and will readily ignite the unconsumed gases of combustion, rendering combustion so complete that visible smoke is practically eliminated.

It will be noted that the collar 62 is provided with a radial flange 62a and the collar 72 with a like flange 73 which will prevent fuel from clogging in the cavity 37 of the feed section 35d.

With the damper 101 set to close the pipe 99, the heated gases of combustion will travel the full length of the passages 97 and 98 of the box-like extensions 94 and through the flue 100 to the chimney, thus providing highly efficient radiating means for heat generated within the combustion chamber 32.

In the specifications and claims, the word "hopper" is intended to include any form of fuel holding device, the words "annular combustion chamber" are intended to include a chamber having similarly arranged walls of any suitable shape.

Having thus illustrated my invention and described the same in detail, what I claim as new and desire to secure by Letters Patent is:—

1. In apparatus for burning solid fuel, an outer wall of inverted, frusto-conical shape, a top wall and an inner wall of frusto-conical shape said walls connected to form an annular combustion chamber, a grate at the bottom of said chamber, a tube formed integrally with said inner wall and projecting upwardly from the lower edge thereof, means for feeding fuel through said tube to the central portion of said grate and means to force the same outwardly into said combustion chamber.

2. In apparatus for burning solid fuel, a suitable shell having an inverted frusto-conical inner wall said shell having walls enclosing an annular combustion chamber, an annular grate at the bottom of said chamber, said grate including a solid plate positioned directly under the conical cavity of said inner wall, a tube for feeding fuel to said grate, said tube extending downwardly through said cavity in spaced relation to said inner wall and a rotary feeding cam for progressively forcing said fuel outwardly from said plate into said combustion chamber.

3. In an apparatus for burning solid fuel, an upright outer wall, a top wall and an inner wall enclosing an annular combustion chamber, a circular grate at the bottom of said chamber, means to impart an intermittent rotary movement to said grate, a rotary cam for moving fuel in an outwardly progressing band from the central portion of said grate to said combustion chamber and means to impart an intermittent rotary movement to said cam in a direction opposite the direction of rotation of said grate.

4. In an apparatus for burning solid fuel, walls enclosing an annular combustion chamber, a circular grate at the bottom of said chamber, means to impart an intermittent rotary movement to said grate, a rotary member having cam arms for moving fuel in an outwardly progressing band from the central portion of said grate to said combustion chamber and means to impart a rotary movement to said rotary member in a direction opposite the movement of said grate.

5. In apparatus for burning solid fuel, walls enclosing an annular combustion chamber, a rotary grate at the bottom of said chamber, said grate having a solid, central portion; means to feed solid fuel to said central portion rotatable, feeding means for progressively moving fuel from

said central portion outwardly into said combustion chamber and means to rotate said grate and feeding means in opposite directions.

6. An apparatus for burning solid fuel, walls enclosing an annular combustion chamber, an annular grate rotatably mounted at the bottom of said chamber, said grate including a solid center plate supporting said grate, means to feed solid fuel to said center plate, a rotatable cam for progressively moving fuel from said center plate outwardly into said combustion chamber and means to rotate said grate and cam in opposite directions.

7. An apparatus for burning solid fuel, an outer wall, an upper wall and an inner wall said walls connected to form an annular combustion chamber, a circular grate at the bottom of said chamber, the inner wall of said chamber extending downwardly to a plane in close, spaced relation to said grate; a hopper mounted within said inner wall for feeding fuel to the central portion of said grate the wall of said hopper spaced inwardly from said inner wall and a cam feeding wheel mounted between the lower edge of said inner wall and the central portion of the grate; means to intermittently release a predetermined quantity of fuel from said hopper to the central portion of said grate and means to provide a relative rotary movement of said feeding wheel and grate to move the fuel thus deposited on said central portion outwardly on said grate.

8. A furnace having an annular combustion chamber, a grate at the bottom of said chamber, an inner wall in the form of an inverted, truncated cone extending downwardly to a plane in close spaced relation to said grate, a fuel supply tube formed integrally with and extending upwardly from the lower edge of said inner wall with the main body of the tube spaced inwardly from said inner wall and means to intermittently feed fuel to said fuel supply tube.

9. A furnace having an annular combustion chamber, a grate at the bottom of said chamber, said chamber having an inner wall in the form of a hollow inverted truncated cone which extends downwardly to a plane adjacent said grate; a tubular extension extending upwardly from the lower edge of said inner wall; said extension terminating at the upper end thereof in a solid end portion; a hopper mounted on said solid portion, a plurality of openings forming circumferentially spaced pockets extending through said upper end portion, means to successively release the fuel from said pockets into said tubular extension and deposit the same on the central portion of said grate and means to force the fuel thus deposited in an outwardly expanding band on said grate.

10. In an apparatus for burning solid fuel, a suitable shell enclosing an annular combination chamber, the inner wall of said shell projecting downwardly in the form of an inverted, hollow truncated cone to a plane adjacent the bottom of said chamber; tubular feed portions projecting upwardly from the lower edge of said inner wall; said feed portions having a solid upper end portion provided with a plurality of chambers spaced around the center thereof and extending vertically therethrough; a hopper supported on said feed portions, a vertical shaft projecting through said hopper and feed portions; means associated with said hopper for rotatably supporting said shaft; a solid plate secured to said shaft in a plane directly below the discharge end of said feed section; an annular grate at the bottom of said combustion chamber, said grate

operatively mounted on said plate; means on the top of said hopper to impart a rotary movement to said shaft and cause a corresponding movement of said grate.

- 5 11. In an apparatus for burning solid fuel, a suitable shell enclosing an annular combustion chamber, the inner wall of said shell being substantially of frustro-conical shape with the truncated end thereof directed downwardly and terminating in a plane adjacent the bottom of said chamber, a tubular feed portion projecting upwardly from the truncated edges of said inner wall, said feed portion having a solid upper end portion provided with an axial bore and having 10 a plurality of circumferentially spaced chambers which extend vertically therethrough; a hopper supported on said feed portion, an upper wall on said hopper, a shaft rotatably supported by said upper wall; said shaft projecting through said hopper and through the axial bore in said feed portion to a point below the bottom of said annular chamber; a solid plate fixed to said shaft directly below the discharge end of said feed portion; an annular grate at the bottom of said 15 combustion chamber, said grate mounted on said plate; a second shaft telescoped over the first named shaft, said second shaft supported by the upper wall of said hopper; valve plates fixed to said second shaft, said plates arranged when rotated to alternately close the upper and lower ends of each of the chambers in said feed portion; a cam feed wheel fixed to the lower end of said second shaft, said cam feed wheel positioned between the delivery end of said feed portion and said plate and means to intermittently rotate said shafts in opposite directions.

- 20 12. In apparatus for burning solid fuel, a suitable shell enclosing an annular combustion chamber, the inner wall of said shell having the lower end thereof terminating in a plane adjacent the bottom of said chamber, a tubular feed portion projecting upwardly from the lower edges of said inner wall; said feed portion having a solid upper end portion provided with an axial bore and a plurality of circumferentially spaced chambers which extend vertically therethrough, a hopper supported on said feed portion; an upper wall on said hopper, a shaft rotatably supported by said upper wall, said shaft projecting through said hopper and through the axial bore in said feed portion to a point below the bottom of said annular chamber, a grate at the bottom of said combustion chamber, said grate mounted on said shaft; a second shaft telescoped over the first named shaft, said second shaft supported by the upper wall of said hopper; valve plates fixed to said second shaft, said plates arranged when rotated to alternately close the upper and lower ends of the chambers in said feed portion, 25 to provide an intermittent feed from said hopper to said grate and means to intermittently impart a rotary motion to said shafts.

- 30 13. In an apparatus for burning solid fuel, a suitable shell enclosing an annular combustion chamber, the inner wall of said shell being substantially of frustro-conical shape with the truncated end thereof directed downwardly and terminating in a plane adjacent the bottom of said chamber, a tubular feed portion projecting upwardly from the truncated edges of said inner wall, a hopper supported on said feed portion; an upper wall on said hopper, a space enclosing casing secured to the upper wall of said hopper and extending downwardly around the hopper in 35 spaced relation thereto and in spaced relation to

said inner wall and terminating in spaced relation above the lower edge of said inner wall, the upper wall of said hopper provided with an opening leading to the space between the hopper and said casing and a grate at the bottom of said chamber. 5

14. In a furnace having an annular combustion chamber, a grate at the bottom of said chamber, said chamber having an inner wall in the form of a hollow inverted truncated cone which extends downwardly to a plane adjacent said grate; a tubular extension projecting upwardly from the lower edge of said inner wall; said extension terminating at the upper end thereof in a solid end portion; a hopper mounted on said solid portion, a plurality of openings forming circumferentially spaced chambers extending through said upper end portion, a rotatable valve plate on the upper side of said solid portion, said valve plate having an opening adapted to be successively brought into register with each of 10 said chambers to fill the chamber with fuel from said hopper and a like valve plate on the lower side of said solid end portion to successively release the fuel from said chambers into said tubular extension and deposit the same on the central portion of said grate and means to force the fuel thus deposited outwardly on said grate. 15

20 15. In a furnace walls forming an annular combustion chamber, a grate at the bottom of said chamber; the inner wall of said furnace 30 extending downwardly and terminating in close spaced relation to said grate, a feeding tube leading downwardly through the cavity of said inner wall, means to intermittently feed solid fuel through said cavity to said grate, said means including a valve positioned above the lower end of said feeding tube, said valve provided with a plurality of chambers, means to successively fill each of said chambers with fuel and means to successively release the fuel from each of said 35 chambers. 40

45 16. In a furnace of the character described, an outer wall, an upper wall and an inner wall, said walls partially enclosing a combustion chamber, a grate at the bottom of said combustion chamber, said inner wall provided with a circumferentially extending bulged area forming a channel on the inner side thereof, a lining on the inner side of said inner wall, said lining covering said channel to provide an air space between the 50 inner wall and the lining, said inner wall having a circumferentially arranged series of bores which extend therethrough and communicate with said air space and a tube communicating with the air outside said casing and leading to said air 55 space.

60 17. In an apparatus for burning solid fuel, an outer wall, an upper wall and an inner wall connected to partially enclose an annular combustion chamber; a circular grate at the bottom 60 of said chamber; the inner wall of said chamber extending downwardly in close spaced relation to said grate; a hopper mounted within said inner wall for feeding fuel to the central portion of said grate, an upper wall on said hopper, a tubular shaft rotatably supported by the upper wall of said hopper and a cam feeding wheel mounted on said shaft in a horizontal plane between the lower edge of said inner wall and said grate; a second shaft rotatably mounted in the first 65 named shaft and projecting from each end thereof, said grate fixed to the second named shaft and means to provide a relative rotary movement of said shafts. 70

75 18. In an apparatus for burning solid fuel, a 75

suitable shell having inner and outer walls enclosing a combustion chamber, the inner wall of said shell projecting downwardly to a plane adjacent the bottom of said chamber, a feed portion projecting upwardly from the lower edge of said inner wall, fuel supplying means operatively connected to said feed portion; said feed portion having a portion provided with a plurality of fuel chambers spaced around the center thereof and extending vertically there-through; a shaft rotatably supported on said fuel supplying means, said shaft projecting through said feed portion, a valve plate fixed to close the lower ends of said fuel chambers, an opening in said valve plate, said opening adapted to be successively registered with said chambers when rotated with said shaft, a second shaft rotatably mounted within the first named shaft, a grate fixed to the second named shaft, means 20 to impart an intermittent rotary movement to said first named shaft and means to impart an opposite rotary movement to the second named shaft.

19. In an apparatus for burning solid fuel, a shell enclosing an annular combustion chamber, a fuel feeding tube leading downwardly through the cavity of the inner wall of said shell, a fuel feeding structure operatively mounted on said

tube, a tubular shaft rotatably mounted in said structure and leading downwardly through said fuel feeding tube, and extending from the upper side of said structure to a plane below said combustion chamber, and a grate forming the bottom of said combustion chamber, said grate mounted on the lower end of said shaft, the bore of said tubular shaft adapted to provide a draft passage leading from the top of said apparatus to the space below said grate. 5

20. In an apparatus for burning solid fuel, a shell enclosing an annular combustion chamber; a fuel feeding tube leading downwardly through the cavity of the inner wall of said shell, a fuel feeding structure operatively mounted on said 15 fuel feeding tube, a tubular shaft leading downwardly through said structure and feeding tube and extending from the upper side of said structure to a plane below said combustion chamber; a grate forming the bottom of said combustion chamber, said grate mounted on the lower end of said shaft, the bore of said shaft adapted to provide a draft passage leading from the top of said apparatus to the space below said grate and adjustable means for controlling 20 the flow of air through the bore of said shaft. 25
